UNITED STATES PATENT OFFICE

152,754

DESIGN FOR PLIERS

Kingston F. Swallow, Milwaukee, Wis.

Application April 19, 1947, Serial No. 138,503

Term of patent 14 years

(Cl. D54—13)

To all whom it may concern:

Be it known that I, Kingston F. Swallow, a citizen of the United States and resident of Milwaukee, in the county of Milwaukee and State of Wisconsin, have invented a new, original, and ornamental Design for Pliers, of which the following is a specification, reference being had to the accompanying drawing, forming part thereof.

Figure 1 is a side elevational view of the pliers showing my new design,

Figure 2 is a plan view of the same, and

Figure 3 is an end elevational view.

I claim:

The ornamental design for pliers, as shown.
KINGSTON F. SWALLOW.
